CLAIM

I claim the ornamental design for a two-piece drinking straw with longitudinal seam, as shown and described.

DESCRIPTION

FIG. 1 is a top perspective view of a two-piece drinking straw with longitudinal seam in the open position, showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a top perspective view of a two-piece drinking straw with longitudinal seam in the closed position, showing my new design;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top plan view thereof; and,

FIG. 14 is a bottom plan view thereof.

1 Claim, 8 Drawing Sheets
